UNITED STATES PATENT OFFICE.

CECIL M. WICKSTRUM, OF OMAHA, NEBRASKA.

TENT.

Application filed February 23, 1923. Serial No. 620,620.

To all whom it may concern:

Be it known that I, CECIL M. WICKSTRUM, a citizen of the United States, residing at Omaha, in the county of Douglas and State of Nebraska, have invented certain new and useful Improvements in Tents, of which the following is a specification.

The present invention relates to improvements in tents and frames for the same.

10 The invention is particularly useful in enclosing the space about graves in cemeteries and aims to provide a collapsible structure which may be erected by a single person without assistance and which permits of 15 folding into a small space for storage or transportation from one to another part of the cemetery.

An object of the invention is to provide 20 a tent of this character which will adapt itself to the uneven ground usually found in cemeteries, to provide an enclosure wherein in the act of lowering the casket into the grave will be obscured from the vision of relatives and in which the device will provide 25 a housing for the ceremonies in inclement weather.

With the foregoing and other objects in view, the invention will be more fully described hereinafter, and will be more particularly pointed out in the claims appended hereto.

In the drawings, wherein like symbols refer to like or corresponding parts throughout the several views:

30 Figure 1 is a perspective view of the improved tent frame.

Figure 2 is an enlarged fragmentary perspective view showing one corner of the frame.

40 Figure 3 is a plan view of a detail.

Figure 4 is a fragmentary perspective view of an enlarged scale showing the joint between the arched members.

Figure 5 is a side view of one of the stakes.

45 Figure 6 is a perspective view of the assembled tent in position over a grave.

Figure 7 shows a side view of a portion of a frame in the collapsed position.

50 Figure 8 is a plan view of the ridge pole, and

Figure 9 is a similar view of one of the side rods.

Referring more particularly to the drawings, 10 designates a grave which we will assume has been recently dug in a cemetery for burial purposes. In Figure 6 this grave

and the surrounding parts are shown to be enclosed by the improved tent which comprises a top 11 side walls 12, a rear wall 13 and front curtains 14 which may be drawn 60 together to enclose the tent entirely or moved apart as indicated in Figure 6 to reveal the interior. If desired the top 11 may be bordered by fringe or other ornamental material indicated at 15.

The frame within the tent is shown in assembled relation in Figure 1 and consists of four tubular posts 16 erected upon stakes shown more particularly in Figure 5 and consisting of pointed shanks 17 adapted to 70 enter the ground and having a shoulder 18 to receive hammer blows by which the stake is driven into frozen ground. A rod 19 extends upwardly from the shoulder and forms a part of the stake, said rod having a series 75 of perforations 20 adapted to register with a perforation through the lower portion of each of the posts 16. Through the alining perforations a pin 21 is inserted. In this way the structure may be made to assume 80 a level position without regard to the character of the ground about the grave.

At the top of each post 16, as shown in Figure 2, forks 22 and 23 are provided to receive the lug 24 which projects down from the arch or top frame bar 25. A shaft 26 passes through the forks 22 and 23 and also through the lug 24 in order to pivotally hold the parts together. The shaft 26 is flattened upon its outer end as indicated at 90 27 to secure it in place at this end. The other end of the shaft carries an angle iron 28 having the perforation 29 indicated in Figure 3 to receive an arm 30 extending from the side spacing rod 31, the end of which abuts against the flattened upper surface of the posts 16.

The rod 31 is shown more particularly in Figure 9 and it carries near its opposite ends two such arms 30 each having perforations 32 in which to receive the locking pins 33 shown in Figure 2. These pins have heads 34 by which they may be inserted and removed and they are likewise inserted through openings 35 made in the arms 36. The arms 36 are pivoted upon the shaft 26 and similar arms 37 are also pivoted upon said shaft, the arms being at opposite sides of each of the posts 16 and being coupled together by cross bars 38 at their outer free ends.

The arch members are preferably of thin

spring steel or some such appropriate material and while they may be made in one piece, they are preferably formed of companion sections 25 and 39 joined together intermediately as by the joint shown in Figure 4 which consists of a single central lug 40 projecting from the member 39 between a pair of similar lugs 41 upon the member 25. Through the intermeshing lugs 10 is passed a pivot pin 42 permitting of the collapse of the sections as indicated in Figure 7. The member 25 is provided with a shoulder 43 arranged in the path of an abutment 44 of the member 39 to restrict the upward opening of these two arch members. At the point is carried an ear 45 projecting downwardly and provided with a perforation 46 to receive the rod 47. This rod extends downwardly and is provided at its 20 lower end with an eye 48 through which passes the cord or wire 49 connected with the opposite bars 38. For instance one of the ends of the wire 49 may be permanently coupled to a rod 38 as indicated at 50 while the other end is provided with a snap hook 51 by which this end is detachably coupled with the opposite bar 38.

The pins 42 in the central joints of the arched members are provided with appropriate webs 52 projecting inwardly from the frames and adapted to receive the down-turned ends 53 of the ridge pole 54 illustrated in Figure 8. When the canvas top 11 is in place, the ridge pole is retained from riding upwardly out of engagement with the webs 52.

In the use of the device, the front and rear frames are of course independent of each other, they being merely coupled by the ridge pole 54. The side rods 31 have no connection with the posts 16 but merely rest against the flat surface thereof and are prevented from disengagement or rotation about the shafts by the presence of the locking pins 33 and the engagement of these pins with the arms 36.

Each of the frames in its folded condition assumes the position indicated in Figure 7, where the two posts are allowed to approach closely to one another, thus occupying only a relatively small space and rendering the structure convenient for carrying about the cemetery. In this condition the arch members 25 and 39 are collapsed downwardly 55 against their respective posts. To assemble the device, the posts are drawn apart and the snap hook 51 engaged with its proper bar 38 from which, in Figure 7 it has been shown separated. The bars 25 and 39 are then pushed upwardly, springing in the position under tension until they assume a position in which the shoulder 43 strikes the abutment 44. In this condition the resiliency character of the arch members will 60 place the cables 49 under tension and the

rods 47 will assume the positions indicated in Figure 1 to further bind these parts together and form a strong construction. Two frames assembled in this manner are erected upon the stakes and adjusted upon the shanks 19 of the stakes until the frame assumes a correct level position. The side bars 31 are then put into position, the arms 30 being inserted through the perforations 29 into angle irons 28 and being locked in position by inserting the pins 33 in place.

By following this up with the adjustment of the ridge pole 54 to the webs 52, the completion of the frame is arrived at and the one requirement is to place the canvas top 80 and sides about the frame. The top is sustained by the arch pieces while the side bars 31 provide for holding the canvas sides and the cables 49, which are under heavy tension, form adequate supports for the rear 85 wall 13 and for the slideable curtains 14 at the front. The curtains may be supported on rings for sliding movement. These curtains may be drawn closed to shut from view the actual operation of lowering the 90 casket into the grave and thus to spare the relatives the unnecessary sorrow of witnessing this harrassing ceremony. The tent also provides an adequate enclosure for housing the funeral party in case of snow 95 or rain or to protect the party from wind and will be found very desirable in winter and in inclement weather. The enclosure may be easily taken down and subsequently erected at another part of the cemetery and 100 the construction is such that it will not suffer by repeated disassembly and erection.

The structure will of course also be found useful for campers and automobile tourists' use on account of its compactness and ease 105 with which it is transported.

I do not wish to be restricted to the size, form, and proportions of the various parts, and obviously changes could be made in the construction herein described without departing from the spirit of the invention, it being only necessary that such changes fall within the scope of the appended claims.

What is claimed is:—

1. In a tent frame construction, supporting posts having openings, angle irons having shafts, said shafts adapted to pass through the openings of the posts, arms pivotally connected to the supporting posts, by the shafts, said angle irons having openings, connecting rods having laterally extended arms formed with openings, said laterally extended arms adapted to pass through the openings of the angle irons, said pivoted arms having openings, and locking pins extending through the laterally extended arms and adapted to pass into the openings of the pivoted arm for securing the supporting posts against movement.

2. In a tent frame construction, supporting

posts, angle irons having openings secured to the supporting posts, connecting rods, laterally extending arms having connection with the connecting rods and adapted to pass through the openings of the angle irons, pivoted arms connected with the supporting posts, and locking pins extending through the laterally extended arms and engaging the pivoted arms for securing the rods against movement with respect to the supporting posts.

3. In a tent frame construction, supporting posts, angle irons secured to the supporting posts and extending inwardly therefrom, said angle irons having openings, con-

necting rods, laterally extended arms forming a part of the connecting rods, and spaced from the ends of the rod to engage the supporting posts, said arms extending through the openings of the angle irons, arms pivotally connected to the supporting posts, and means carried by the laterally extended arms and adapted to engage the arms mounted on the supporting posts for restricting movement of the rods with respect to the supporting posts.

In testimony whereof I have affixed my signature.

CECIL M. WICKSTRUM.
